LESLIE N. CRICHTON, OF EDGEWOOD PARK, PENNSYLVANIA, ASSIGNOR TO WESTINGHOUSE ELECTRIC & MANUFACTURING COMPANY, A CORPORATION OF PENNSYLVANIA.

RELAY.

Application filed July 30, 1920. Serial No. 400,093.

My invention relates to relays and particularly to relays for protecting electrical distributing systems against grounds.

One object of my invention is to provide 5 a relay system for disconnecting a feeder circuit when a ground occurs thereon.

Another object of my invention is to provide a relay, for the above-indicated operation, that shall not be operated by currents 10 that are produced by third harmonics.

A further object of my invention is to provide a power-responsive relay, for the above operation, that shall be very sensitive to small values of current, and that shall be 15 simple and reliable in its operation.

Heretofore, relays for protecting electric circuits against grounds have been inserted in the common neutral conductor between current transformers and the overload relays. Such relays, however, have not been 20 satisfactory because they required too much energy to operate, or, required additional current transformers in systems wherein the ratios of the transformers that were employed for the instruments and other relays 25 were too high for the ground relay. Other relays and systems were not adequately protective because selective operation was not obtained when the value of the ground current was less than the value of normal load 30 current and the relays were not selective because of the difficulty in obtaining an inverse time element in the operation thereof and because the relay had no directive element. Such relays were further undesirable 35 since they were responsive to third harmonics in the system to which they were connected.

In view of the above conditions, I provide 40 a power-responsive relay that has its potential winding connected across the terminals of a resistor in the grounded neutral conductor of the system and that has its current winding in circuit with the common neutral conductor between the current transformers and overload relays or instruments. The power-responsive relay is thus sensitive

to small currents that may result from leakage to ground because of the co-operation between the two windings, and is unaffected 50 by any currents that may result from third harmonics in the system.

A ground protecting system embodying this relay overcomes the above-mentioned disadvantages since little energy is required 55 and since the relay is selective, in that it has both a directive and an inverse-time-element characteristic in its operation, and is not responsive to third harmonics in the system.

Figure 1 of the accompanying drawings is a diagrammatic view of a system embodying my invention;

Fig. 2 is a diagrammatic view of the system that is illustrated in Fig. 1, illustrating 65 the distribution of the ground current; and

Fig. 3 is a diagrammatic view of a system including a plurality of feeder circuits.

A source 1 of electromotive force supplies energy to a supply circuit 2 from which 70 energy is transmitted to a distributing circuit 3 through a circuit interrupter 4. The distributing circuit 3 is provided with a plurality of current transformers 5 for energizing a plurality of overload relays 6 75 and a ground relay 7. The current winding 8 of the relay 7 is connected in circuit with the common neutral conductor 9 between the current transformers 5 and the overload relays 6. The potential winding 10 of 80 the relay 7 is connected across the terminals of a limiting resistor 11 that is connected, by a conductor 12, between ground 13 and the neutral point of a plurality of potential transformers 14 that are connected in Y- 85 relation to the conductors of the supply circuit 2.

A safety resistor 15 is provided in parallel relation to the winding 10 of the relay 7 to prevent injury thereto by reason of large 90 potential differences across the resistor 11.

The interrupter 4 is provided with a tripping magnet 16 that is energized to trip the breaker when the relay 7 operates. The re-

lay 7 is adapted to actuate its contact members 17 to trip the interrupter 4 only when a ground occurs on a conductor in the distributing circuit 3.

- 5 When a ground occurs upon a conductor 18 of the circuit 3 at the point A, a circuit is completed from the source 1 of electromotive force through the conductor 18, the ground, the ground resistor 11, the potential 10 transformers 14 and the conductors of the supply circuit 2 back to the source 1. Potential is now established across the terminals of the ground resistor that serves to energize the potential winding 10 of the 15 relay 7. The unbalanced current in the conductor 9, that is caused by the traversal of current through the ground circuit, energizes the current winding 8 of the relay 7. The two windings of the relay 7 co-operate 20 to effect engagement of the contact members 17 and energize the tripping magnet 16 to trip the interrupter.

A definite distribution of the resulting ground current has been observed in such 25 a system, as is illustrated in Fig. 2. The ground current traverses the ground and the grounded neutral conductor 12 and then divides equally between the three potential transformers. One-third of the ground 30 current traverses each conductor of the supply circuit 2 between the points of connection of the potential transformers 14, and of the conductors of the faulty feeder circuit 3, to the supply circuit 2. Beyond 35 the terminals of the feeder circuit 3, one-third of the ground current traverses each of the two normal phase conductors toward the source 1 of electromotive force. The faulty phase conductor between the 40 feeder conductor terminal and the source 1 of electromotive force is traversed by two-thirds of the ground current. At the terminal of the faulty feeder conductor, the two-thirds of the ground current combine 45 with the one-third that traverses the circuit 2 between the potential transformer terminal and the faulty feeder conductor terminal.

The effect of the ground current is equivalent to the superposition of a single-phase 50 electromotive force upon the circuit comprising the faulty conductor as one conductor, and the two normal conductors combined as the other conductor, of a circuit. 55 One-third of the ground current traverses only the faulty conductor, the ground and the potential transformer that is connected to the corresponding conductor in the supply circuit. This third does not traverse 60 the source 1 of electromotive force, but is induced in the primary winding of the transformer connected to the faulty conductor by the circulating current that has been induced in the secondary windings of

the potential transformers by the ground 65 currents traversing the primary windings of the other two transformers.

The secondary windings of the potential 70 transformers 14 may be employed to provide potential for measuring instruments, etc. and need not, therefore, be of special design or construction.

Since the ground current that traverses the current winding 8 of the ground relay 7 is in phase with the current that traverses the grounded neutral conductor 12, the relay 7 may be made so directive and selective as to select and isolate a faulty feeder circuit 75 in an electrical distributing system.

The factors that are required for the 80 operation of the relay 7 are the unbalance effects that are produced both in the currents that traverse the conductors of the feeder circuit 3 and in the effective ground currents that traverse the windings of the 85 potential transformers.

Although a generator 1 is shown, it is obvious that the protective system illustrated is readily applicable to a transformer substation and that modifications may be 90 made in the arrangement of the current and potential transformers to obtain the effects required to operate the relay without departing from the spirit and scope of the invention as set forth in the appended 95 claims.

I claim as my invention:

1. In a polyphase distributing system, the combination with a plurality of current 100 transformers connected in series with the conductors thereof, and a plurality of potential transformers connected between each conductor and ground through a common current-limiting resistor, of a relay having two co-operating windings, one of which is 105 responsive to unbalance in the current transformers and the other of which is responsive to a traversal of current in the current-limiting resistor.

2. In a polyphase distributing system, the combination with a source of energy, a plurality of feeder conductors and an interrupter connected therebetween, of a plurality of current transformers energized from the feeder conductors, a plurality of potential transformers connected from the source of energy to ground through a common current-limiting resistor, means for actuating the interrupter and a relay for energizing the interrupter actuating means comprising 115 means responsive to an unbalance in the currents traversing the current transformers and means responsive to a current traversing the current-limiting resistor.

3. In a polyphase distributing system, the combination with a plurality of feeder conductors and a plurality of star-connected 120 current transformers energized thereby, of

means in the neutral common path of the relays severally responsive to a ground current in the feeder circuit and to a corresponding current in the supply circuit for selectively isolating the faulty feeder circuit.

5 means in the neutral common path of the relays severally responsive to a ground current in the feeder circuit and to a corresponding current in the supply circuit for selectively isolating the faulty feeder circuit.

4. In a distributing system, the combination with a supply circuit, a plurality of feeder circuits and a plurality of connecting

means therebetween, of a plurality of watt

10 In testimony whereof, I have hereunto 15
subscribed my name this 19th day of July,
1920.

LESLIE N. CRICHTON.
